UNITED STATES PATENT OFFICE

159,404

STOCKING

Erich Boettcher, Southampton, Pa.

Application April 11, 1949, Serial No. 1,904

Term of patent 3½ years

(Cl. D47—7)

To all whom it may concern:

Be it known that I, Erich Boettcher, a citizen of the United States, residing at Southampton, in the county of Bucks, State of Pennsylvania, have invented a new, original, and ornamental Design for Stocking, of which the following is a specification, reference being had to the accompanying drawing, forming part thereof.

Figure 1 is a side elevational view of a woman's full-fashioned stocking, showing my novel design.

Figure 2 is a rear elevational view of the same.

Figure 3 is an enlarged rear elevational view of the heel portion of the stocking disclosed in Figure 2.

Figure 4 is an enlarged side elevation of the foot portion of the stocking as disclosed in Figure 1.

The dominant feature of my design resides in the shape and arrangement of the reinforced area of the stocking at and above the heel and in the arrangement of lines of small openings formed in said reinforced area.

I claim:

The ornamental design for a stocking, as shown and described.

ERICH BOETTCHER.
